UNITED STATES PATENT OFFICE.

CHARLES G. HERBERT, OF DETROIT, MICHIGAN.

STARTING MECHANISM FOR GAS-ENGINES.

No. 846,106.

Specification of Letters Patent.

Patented March 5, 1907.

Application filed March 20, 1905. Serial No. 250,900.

To all whom it may concern:

Be it known that I, CHARLES G. HERBERT, a citizen of the United States, residing at Detroit, county of Wayne, State of Michigan, have invented a certain new and useful Improvement in Starting Mechanism for Gas-Engines; and I declare the following to be a full, clear, and exact description of the same, such as will enable others skilled in the art to which it pertains to make and use the same, reference being had to the accompanying drawings, which form a part of this specification.

This invention relates to starting mechanism for gas-engines; and the object of my improvements is to provide an improved automatic apparatus for giving the crank-shaft of a gas-engine an initial motion of rotation.

In the drawings, Figure 1 is a longitudinal section of an apparatus embodying my invention. Fig. 2 is a similar view to Fig. 1, a portion of the apparatus shown in section in Fig. 1 being shown in full in this figure and a portion of the apparatus being shown in different operative position, the spring being unwound. Fig. 3 is a section on the line 3-3 of Fig. 1 looking from the left of said figure. Fig. 4 is a section on the line 4-4 of Fig. 1 looking from the left of said figure. Fig. 5 is a detail view showing the lower end of the bolt L.

F is a central shaft, which may be a prolongation of the crank-shaft of the motor.

B is a sleeve surrounding the shaft F.

O is a drum surrounding the shaft F and having one of its ends open. At one end the drum O is extended in a hub O¹, which surrounds a stationary arbor consisting of a steel bushing I, keyed to a stationary support Q. z z are lugs by which the support Q may be secured to a proper stationary object.

C is a clutch-ring in the sleeve B, secured thereto by dowel-pins g. The ring C is provided at its interior surface with bevel-surfaced grooves.

D' is a steel bushing surrounded and keyed to the shaft F. Into the grooves in the ring C, bearing against the bevel surfaces and against the bushing D', are rollers D. These rollers permit free rotation of the shaft F relative to sleeve B in the opposite direction to that of the hands of a clock, but prevent a rotation of said sleeve relative to said shaft in the same direction, Fig. 3.

A is a spiral spring, one end of which is secured at O¹ to the drum O and the other at

A', Fig. 3, to the sleeve B. The action of said spring is to tend to turn the sleeve B in the opposite direction to that of the hands of a clock, and when the drum O is rotated in that direction; the sleeve B being held still the action is to wind up the spring A.

J is a clutch-ring keyed to the interior of the hub O¹ and surrounding the bushing I. The interior of the ring J is grooved, forming bevel surfaces.

R are rollers adapted to act against the bevel surfaces on the ring J and against the periphery of the bushing I to form a clutch which shall prevent any rotation of the drum O in the direction of the hands of a clock, but shall permit a rotation of said drum in the other direction, Fig. 4.

H is a sleeve connected to the bushing I by a spline and groove, so that it may slide longitudinally, but may not turn relative to said bushing.

h is an annular lug or projection formed around the inner end of the sleeve H.

X is a helical spring around the sleeve H, abutting against a shoulder on the sleeve I at one end and against the lug h at the other end. The spring X acts to press the sleeve H inward.

H' are ratchet-teeth upon the inner end of the sleeve H, and B' are ratchet-teeth on the adjacent end of the sleeve B. When the sleeve H is in its inward position, the teeth H' engage with the teeth B' and prevent any rotation of the sleeve B.

P is a disk secured to the shaft F by being keyed to the bushing D' and closing the otherwise open end of the drum O. The periphery of the disk P extends beyond the periphery of the drum O for the greater part of its circumference, but is cut away for a short distance to form a notch p.

M is a bolt secured upon the periphery of the drum O and adapted to slide transversely thereto in ways m m.

n is a slot in one end of the bolt M.

N is a latch provided with a tooth adapted to engage in the slot n to hold the bolt M in its retracted or left-hand position.

When the bolt M is forced to the right, Figs. 1 and 2, it engages in the notch p and binds the drum O and disk P together, thus forming a lock for connecting the drum O with the shaft F and releasing the same.

b are screw-threads upon the sleeve B.

S is a nut upon the sleeve B; its threads engaging the threads b.

L is a bolt mounted upon the drum O, having one end against the latch N and the other end contacting the sleeve H.

L' is a yoke upon the drum O.

5 T is a spring, one end of which presses against the yoke L' and the other end against the bolt L and acting to press said bolt inward.

K is a flat cam having a beveled surface at 10 one end, secured at the other end to the nut S, and at the beveled end passing through a slot in the bolt L.

V U is a spring extending outward from 15 the bolt K or nut S and at its outer end engaging in the slot n.

The operation of the above-described device is as follows: The spring A being supposed to be wound up, the sleeve H is drawn outward, disengaging the teeth H' and B'.

20 The spring A is now acting upon the drum O, tending to turn it in one direction, and upon the sleeve B, tending to turn it in the other direction. Under these conditions rotation of the drum O is prevented by the clutch-rollers R, and the sleeve B is bound to the shaft F by the rollers D, so that the spring rotates said shaft until the engine commences to act.

25 When the ratchet-teeth H' and B' are disengaged, as above described, the nut S is at the left-hand end of its travel, as shown in Fig. 1.

30 When the sleeve H is drawn out, the bolt L is forced in front of the lug h by its spring T, thus preventing the spring X from pressing said sleeve inward to reengage the ratchet-teeth H' B'.

35 When the sleeve B rotates as above described, the drum O, and consequently the nut S, remaining stationary, said nut is drawn inward, carrying with it the bolt K and pressing the

40 latch L upward by means of the cam-surface on K disengaging the sleeve H and allowing it to move inward under the pressure of the spring X to engage the sleeve B and prevent its further rotation.

45 At the same time the upper end of the bolt L strikes against the latch N, disengaging the bolt M. (See Fig. 2.)

When that nut S moves inward, as above described, it carries with it the lower end of the spring U V, thus bringing a resilient pressure

50 through said spring upon the bolt M, tending to throw it into the notch p, engaging the drum O with the disk P. The disk P being carried by the shaft F, which is now being

driven by the engine, causes the drum O to rotate, winding up the spring A. The drum O carries with it the nut S, turning the same upon the sleeve B and causing it to move, because of its engagement with the threads b, to its left-hand position, as shown in Fig. 1. At this position the bolt M is again retracted and the drum O and disk P separated. Everything is now in the initial position, and the series of operations may be repeated.

What I claim is—

1. In an apparatus of the kind described, 65 the combination of a movable part a clutch part H, adapted to engage said movable part of said apparatus and be disengaged therefrom, a spring acting to reengage said part when disengaged, a catch adapted to hold 70 said part out of engagement against the action of said spring, and means operated by the relative motion of the parts of said apparatus for releasing said catch to permit it to engage said movable part.

2. In an apparatus of the kind described, 75 the combination of the relatively movable parts B and O, a part S actuated by the relative movement of said parts, a lock upon the part O, a spring upon the part S connected 80 with the bolt of said lock and adapted to act in different directions at the two ends of the travel of the part S, a restraining-catch for said lock and means for actuating said catch.

3. The combination of the shaft F, sleeve 85 B, clutch between said sleeve and shaft, said sleeve being provided with screw-threads, drum O, nut S on said drum engaging said screw-threads, a clutch between said drum and a stationary arbor, part H adapted to 90 secure sleeve B from rotation and releasing the same, a bolt L adapted to prevent the engagement of part H with sleeve B, a bolt on said drum adapted to engage and disengage said drum with said shaft, means connecting said nut with each of said bolts so that the movement of said nut shall actuate said bolts, substantially as shown and described.

In testimony whereof I sign this specification in the presence of two witnesses.

CHARLES G. HERBERT.
